(57) **CLAIM**

The ornamental design for a storage container, as shown and described.

DESCRIPTION

FIG. 1 is a top front perspective view of a storage container showing my new design;

FIG. 2 is a bottom rear perspective view thereof;

FIG. 3 is a front elevated view thereof;

FIG. 4 is a rear elevated view thereof;

FIG. 5 is a top plan view thereof;

FIG. 6 is a bottom plan view thereof;

FIG. 7 is a right elevated view thereof;

FIG. 8 is a left elevated view thereof;

FIG. 9 is a vertical cross-sectional view taken in the direction of line 9-9 in FIG. 4;

FIG. 10 is a vertical cross-sectional view taken in the direction of line 10-10 in FIG. 7;

FIG. 11 is a horizontal cross-sectional view taken in the direction of line 11-11 in FIG. 8; and,

FIG. 12 is a top front perspective view thereof, showing the storage container in a closed configuration.

The broken lines showing of a lid in FIGS. 1-5, 7-10, and 12 are included for the purpose of showing environmental structure and form no part of the claimed design.
